(57) **CLAIM**

We claim the ornamental design for hinge for a multi-position ladder, as shown and described.

DESCRIPTION

FIG. 1 is a right side elevation view of a hinge for a multi-position ladder showing our new design;

FIG. 2 is a front elevation view thereof;

FIG. 3 is a top plan view thereof;

FIG. 4 is a front right perspective view thereof; and,

FIG. 5 is a front left perspective view thereof.

The broken lines shown in the figures are included for the purpose of illustrating portions of the hinge for a multi-position ladder and form no part of the claimed design.
